UNITED STATES PATENT OFFICE.

GEORGE BAKER AND ISAAC BULLOCK, OF LIMA, PENNSYLVANIA.

IMPROVEMENT IN SOAPS.

Specification forming part of Letters Patent No. 117,722, dated August 8, 1871.

To all whom it may concern:

Be it known that we, GEORGE BAKER and ISAAC BULLOCK, of Lima, in the county of Delaware and State of Pennsylvania, have invented a new and useful Soap; and we do hereby declare the following to be a clear and exact description of the nature thereof, sufficient to enable others skilled in the art to which our invention appertains to fully understand and use the same.

Our invention consists of a soap which has many advantages, some of which will be herein-after set forth.

In carrying out the invention we proceed as follows: Take ten (10) pounds of "join" and two and a half ($2\frac{1}{2}$) quarts of lye made of water and soda ash. These are placed in a kettle over the fire, and to them are added two (2) ounces of pearl-ash and two and a half ($2\frac{1}{2}$) ounces of borax, brought to a boil and then well stirred. This constitutes the body of the soap, and to it are added eight (8) ounces of turpentine, eight (8) ounces of benzine, seven (7) ounces of ammonia, one-half ($\frac{1}{2}$)

pound of cocoanut or oil of lavender, and four (4) pounds of Chinese preparation.

It will be seen that we have produced a perfectly white soap. By its use clothes require no bluing. It has no deleterious substances in it, resin, sal-soda, &c., being dispensed with, and is alike useful for the laundry and toilet. It will wash in any kind of water, whether cold or warm, soft or hard.

Having thus described our invention, what we claim as new and desire to secure by Letters Patent, is—

The within-described soap, compounded of the ingredients in the manner and about the proportions set forth.

To the above we have signed our names this 6th day of July, 1871.

GEORGE BAKER.
ISAAC BULLOCK.

Witnesses:

A. H. PENNELL,
JOHN ATKINSON.
